UNITED STATES PATENT OFFICE.

JOHN SLATER, OF BURSLEM, ASSIGNOR TO HENRY DOULTON & CO., OF LONDON, ENGLAND.

DESIGN FOR A VASE.

SPECIFICATION forming part of Design No. 23,465, dated July 17, 1894.

Application filed May 31, 1894. Serial No. 513,083. Term of patent 3½ years.

To all whom it may concern:

Be it known that I, JOHN SLATER, a subject of the Queen of Great Britain, residing at Burslem, Staffordshire, England, have invented or produced a new and original Design for Vases, of which the following is a specification.

This design has for its object to provide a novel and ornamental vase which presents a characteristic and distinguishing appearance to the eye.

The design consists of a vase having a base portion and a body which widens upwardly, and is provided with prominent spiral undulations extending from the base portion to the top or upper edge.

The design is illustrated by the accompanying drawing, in which the figure is a side elevation of the vase.

In the accompanying drawing, it will be seen that the vase is composed of a base portion 1 and a body portion which widens toward the top or upper edge 2, and is provided with spiral undulations 3 which are quite prominent and run from the base portion to the top or upper edge of the body.

The design provides a vase which presents an ornamental and handsome appearance.

What I claim is—

The design for a vase, substantially as shown and described.

In testimony whereof I have hereunto set my hand in presence of two subscribing witnesses.

JOHN SLATER.

Witnesses:

LEONARD WILLIAM LANGLEY,
ROBERT ALLEN.
